Application June 24, 1936, Serial No. 87,076

3 Claims. (Cl. 30—13)

This invention appertains to new and useful improvements in tools and more particularly to metal cutting snippers.

The principal object of the present invention is to provide snippers particularly adapted for cutting sheet metal bands and like material.

Another important object of the invention is to provide a tool of the character stated which will be handy to operate, positive acting and not susceptible to the development of frequent defects.

These and various other important objects and advantages of the invention will become apparent to the reader of the following specification.

In the drawings:—

Figure 1 represents a side elevational view of the tool.

Figure 2 represents an elevational view looking at the opposite side from that shown in Figure 1.

Figure 3 represents respective use of the two main portions of the tool.

Referring to the drawings wherein like numerals designate like parts, it can be seen that the tool is made up of the handles 5—6, the handle 5 being provided with an arcuate depression 6 in one side thereof for receiving the curved end portion 7 of the blade 8, this blade being pivotally secured to the handle 5 as at 9.

The end portions of this blade 8 are beveled as at 10 for engagement into the undercut end walls 11—11 of the depressed portion 12 in the head 13 of the handle 6. This head 13 is bifurcated as at 14, defining the parallel leg portions 15—16. The portion 16 is tapered off as at 17 and acts as a wedge or guide in getting the implement behind a band so that the band can be brought into the bifurcation 14.

The leg portion 15 is provided with a reduced extension 18 having the opening 19 therein.

A pair of link members 20—20 are pivotally connected as at 21 to the overlying portion of the handle 5. As is shown in Figure 1, the openings 22 in the links 20 register with the opening 19 in the reduced portion 18 and a pivot pin 23 is disposed through these openings, whereby the handle 5 is pivotally connected to the head portion 13 of the handle 6.

Obviously by contracting the handles 5—6, the cutting edge of the blade 8 is brought across the bifurcation 14 on a bias so that any sheet material in this bifurcation will be snipped off.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

1. Snippers of the character described comprising a pair of handle members, one of said handle members being provided with a head portion to which the other handle member is pivotally connected, said head portion being bifurcated, a blade slidable transversely on the head and being pivotally connected to the last-mentioned handle, said head being provided with a guide for the blade, 15 said guide traversing the said bifurcation.

2. Snippers of the character described comprising a pair of handle members, one of said handle members being provided with a head portion to which the other handle member is pivotally connected, said head portion being bifurcated, a blade slidable transversely on the head and being pivotally connected to the last-mentioned handle, 25 said head being provided with a guide for the blade, said guide traversing the said bifurcation, 30 said blade having a cutting edge operating on a bias with respect to the said bifurcation.

3. Snippers of the character described comprising a pair of handle members, one of said handle members being provided with a head portion to which the other handle member is pivotally connected, said head portion being bifurcated, a blade slidable transversely on the head and being pivotally connected to the last-mentioned handle, 35 said head being provided with a guide for the blade, said guide traversing the said bifurcation, 40 said head having one of its furcations tapered at its free end.
